Des. 241,659
Patented Sept. 28, 1976

241,659

RELIGIOUS DISPLAY

Wiley H. Dill, 2002 Gall Ave.,
Albany, Ga. 31705

Filed Feb. 22, 1973, Ser. No. 334,946

Term of patent 14 years

Int. Cl. D11—02

U.S. Cl. D11—157

FIG. 1

FIG. 2

FIG. 3

FIG. 4

FIG. 5

FIG. 6

FIG. 7

FIG. 1 is a perspective view of a religious display showing my new design;

FIG. 2 is a front elevational view;

FIG. 3 is a side elevational view;

FIG. 4 is a top plan view;

FIG. 5 is a perspective view of a religious display showing a modified form of my new design;

FIG. 6 is a front elevational view thereof; and

FIG. 7 is a top plan view thereof.

I claim:

The ornamental design for a religious display, as shown and described.
